N. LEIDGEN.

HAIR WASHER.

APPLICATION FILED APR. 10, 1905.

2 SHEETS—SHEET 2.

UNITED STATES PATENT OFFICE.

NICOLAUS LEIDGEN, OF MILWAUKEE, WISCONSIN, ASSIGNOR OF ONE-HALF TO EDWARD H. MUNKWITZ, OF MILWAUKEE, WISCONSIN.

HAIR-WASHER.

No. 800,660.

Specification of Letters Patent.

Patented Oct. 3, 1905.

Application filed April 10, 1905. Serial No. 254,668.

To all whom it may concern:

Be it known that I, NICOLAUS LEIDGEN, a citizen of the United States, residing at Milwaukee, in the county of Milwaukee and State of Wisconsin, have invented certain new and useful Improvements in Hair-Washers, of which the following is a specification, reference being had to the accompanying drawings, forming a part thereof.

The main object of this invention is to facilitate cleaning hair removed from hides in tanneries.

It consists in certain novel features of construction and in the peculiar arrangement and combinations of parts hereinafter particularly described and claimed.

In the accompanying drawings like letters designate the same parts in the several figures.

Figure 1 is a vertical longitudinal section on the line 1 1, Fig. 2, of a machine embodying my invention. Fig. 2 is a plan view of the same; and Fig. 3 is a vertical cross-section thereof on the line 3 3, Fig. 2.

a designates an oblong vat, which is for convenience preferably sunk below the floor of the tannery in which the machine is intended to be used. This vat has a depression *b* in the bottom at one end, forming a settling space or tank below the general level of the bottom of the vat, and in the bottom of this depression is a waste-opening *c*, which is located near the end of the vat and is provided with a plug or stopper *d* for temporarily closing it. A gate and overflow board or plate *e*, standing normally across the vat adjacent to the waste-opening *c*, is fitted to be moved up and down in vertical guides on the sides of the vat. A perforated plate or screen *f* is arranged horizontally over the depression *b* in the vat and is curved upwardly and attached at its outer end to a cross-support *g*. The main portion of this screen is located at the level of the bottom of the main part of the vat and forms a continuation thereof.

The hair-washing machine constituting the present invention is designed more particularly to be used in tanneries in connection with one or more unhairing-machines, the frame *h* of one of which is shown in the drawings.

The base of the unhairing-machine is shown as sunken below the general floor-level, and an inclined chute *i*, located underneath the unhairing-machine, opens at its lower end into one side of the vat *a* below the top of the gate

e, which determines the liquid-level therein. 55 The vat is provided with an endless conveyer consisting of a link belt *j*, running over sprocket-wheels *k* at or near opposite ends of the vat and provided with transverse floats *l*, which travel on the under side of the conveyer 60 along the bottom of the vat toward and over the screen *f*, and on the upper side of the conveyer in an opposite direction near the liquid-level in the vat. To prevent the belt and floats from sagging on the upper side of the 65 conveyer between the sprocket-wheels, horizontal guides *m* are attached to the sides of the vat in position to engage with and support the floats *l* at the proper level.

An elevator for removing the cleansed hair 70 from the vat consists of an endless link belt *o*, running in an inclined position over sprocket-wheels *p* and provided at intervals with strainer buckets or vanes *q*, the lower sprocket-wheel *p* being arranged in the vat *a* adjacent 75 to the sprocket-wheel *k* at the end of the conveyer opposite the overflow-board *e*. The elevator may be driven, as shown in Fig. 1, by a link belt *r* from a counter-shaft overhead or by any other suitable driving connection, and 80 the conveyer may be driven from the elevator by a link belt *s*, connecting sprocket-wheels on the shafts at their adjacent ends, as shown in Fig. 2. The vat *a* is supplied with water at or near the end opposite its overflow through 85 a hose or pipe *t*.

The machine operates as follows: The vat *a* being filled with water to the top of the overflow-board *e*, as shown in Figs. 1 and 3, and the conveyer and elevator being driven 90 in the direction indicated by arrows on Fig. 1, the hair falling from the unhairing-machine into the chute *i* is discharged therefrom at its lower end into the vat *a* below the level of the liquid therein and between the 95 upper and under sides of the conveyer. By reason of the dirt and foreign matter adhering to the hair as it comes from the unhairing-machine it sinks to the bottom of the vat and is carried by the floats *l* on the under side 100 of the conveyer toward and over the screen *f* and in its passage is washed, the dirt for the most part passing through the perforated plate or screen *f* and settling in the space or tank *b* below it. As the hair is freed from 105 dirt and foreign matter it becomes more buoyant and tends to rise to the surface of the liquid or cleansing solution in the vat, where

it is caught by the floats *f* on the upper side of the conveyer and carried toward the opposite end of the vat away from its overflow, being thoroughly rinsed and cleansed by the 5 counterflow of fresh water supplied to the vat through the hose or pipe *t*. The cleansed hair delivered from the conveyer is taken up by the vanes *g* of the elevator and drained during its ascent, being discharged at the top of 10 the elevator upon the floor or into a suitable receptacle provided for it. The vat is flushed, and the dirt accumulating in the catch-basin or settling-tank *b* is removed from time to time by raising the gate *e* and allowing the 15 water and dirt contained in the tank to flow directly into and drain off through the waste-opening *c*. To balance the pressure on the gate *e* and facilitate opening it, the waste-opening *c* is temporarily closed by the plug 20 or stopper *d* until the overflow rises in the compartment in which the waste-opening is located to the level of the water or liquid in the main portion of the vat. The gate can then be easily raised, and the plug or stopper 25 *d* being removed the contents of the vat will obviously run off through the waste-opening.

Various changes in the details of construction and in the arrangement of parts of the apparatus may be made without materially 30 affecting its mode of operation and without departing from the spirit and intended scope of the invention.

I claim—

1. In a hair-washer the combination of a vat 35 having an overflow at one end and a depression in the bottom, a screen over said depression, and an endless conveyer provided with floats which are movable along the under side of the conveyer over the bottom of the vat 40 toward and over said screen and along the upper side of the conveyer in the opposite direction, substantially as described.

2. In a hair-washer the combination of a vat 45 having a depression in the bottom at one end, a screen over said depression, an endless conveyer provided with floats which are movable on the under side over the bottom toward said screen and on the upper side in the opposite direction, and an elevator arranged to remove 50 the cleansed hair from the end of the vat opposite said depression, substantially as described.

3. In a hair-washer the combination of a vat 55 having a depression and a waste-opening in the bottom at one end, an overflow-gate adjacent to said opening, and a conveyer provided with transverse floats adapted to travel on the under side toward and over said screen and on the upper side in the opposite direction

adjacent to the liquid-level in the vat, substantially as described.

4. In a hair-washer the combination of a vat having a depression in the bottom and an overflow at one end, a screen over said depression, an endless conveyer provided with floats 65 which travel on the under side of the conveyer toward and over said screen and on the upper side in the opposite direction, and an elevator comprising an endless belt dipping at its lower end into said vat adjacent to the 70 end of the conveyer opposite said screen and provided with strainer-buckets, substantially as described.

5. In a hair-washer the combination of a vat having a depression and a waste-opening in 75 the bottom at one end, a screen arranged horizontally over said opening at the level of the higher portion of the bottom, a movable gate and overflow-plate standing normally across the vat adjacent to said opening, a stopper for 80 closing said waste-opening, and a conveyer provided with transverse floats arranged to travel along the bottom of the vat toward and over said screen and on the upper side of the conveyer in the opposite direction close to the 85 surface of the liquid in the vat, substantially as described.

6. In a hair-washer the combination of a vat having a depression in the bottom and an overflow at one end and a feeding-chute at one 90 side arranged to introduce hair into the vat below the liquid-level therein, a horizontal screen arranged over said depression and forming a continuation of the higher part of the bottom of the vat, and an endless conveyer 95 provided with floats adapted to travel on the under side of the conveyer along the bottom of the vat toward and over said screen and on the upper side in the opposite direction close to the liquid-level in the vat, substantially as 100 described.

7. In a hair-washer the combination with a vat having a horizontally-disposed screen, a settling-space below the screen and an overflow 105 at one end above the screen, of an endless conveyer provided with floats which are arranged to travel on the under side of the conveyer over said screen, and on the upper side of the conveyer away from said overflow adjacent to the level thereof, substantially as 110 described.

In witness whereof I hereto affix my signature in presence of two witnesses.

NICOLAUS LEIDGEN.
